DEVICE FOR AUTOMATICALLY WRITING
THE MUSIC PLAYED ON INSTRUMENTS
PROVIDED WITH KEYBOARD OR IN ANY
CASE WITH FIXED TUNING

Juriy Bärsuk, Genoa, Italy

Application October 18, 1933, Serial No. 694,144
In Italy October 26, 1932

6 Claims. (Cl. 84—461)

The present invention relates to a device by means of which it is possible to print music automatically and with the usual notation as it is played on an instrument provided with keyboard.

The device enables the composer to play with absolute freedom the composition on the keyboard of the musical instrument and simultaneously it transcribes the composition itself.

10 In the accompanying drawing wherein the invention is illustrated:—

Figure 1 is a diagrammatic view of one form of music printing device.

15 Fig. 2 is a similar view of a second form of the device.

With reference to Fig. 1, 1 denotes the keyboard, 3 the paper roll to be utilized for printing mounted upon a support 4 which is suitably retarded to prevent the paper strip from freely 20 unrolling. 6 indicates the paper strip wound around the receiving roll 7 mounted on the shaft 8 and suitably tensioned as by means of a spring motor designated generally at 13 to cause said roll to take up the paper strip.

25 10, 11 and 12 are guide rollers, and 14 is a motor having a shaft 15 and a speed changing device, which is represented by the two conical rollers 16 and 17, the belt 18 and a belt shifter 19. The shaft 15 drives the conical gear 20 which can alternately engage either the conical gear 21 or the gear 22, by means of the shift device 23 mounted on the shaft 24 which latter will thus receive rotary motion in either direction and with the desired speed. On the shaft 24 is 30 mounted the driving roller 25 for the motion of the paper strip necessary for the writing of the music. The roller 25 is in contact with the paper strip 6 which is held between the roller 25 and a pressure roller 26 urged in the direction 35 of the arrow 27 whereby if the roller 25 is caused to rotate in the one direction, the paper sheet or ribbon 6 will move in the direction of the arrow 29, unwinding from the shaft 4 and 40 winding around the shaft 8, and will remain in any case well stretched throughout.

45 At a point 30 in the height of the vertically disposed portion of the strip 6 between the guide rollers 10 and 11 is located a magnet 31, the core 50 of which terminates in a point (or marking device), and can be placed before a writing ribbon 33 that is continually displaced in normal direction to the drawing sheet by means of a conventional ribbon shifting device. The dis- 55 tance between the points 30 and 34 corresponds

to a note having a time value of 1/64th $\frac{1}{4}$ of four quarters of normal time; the distance between 30 and 35 corresponds to $\frac{1}{2}$ nd $\frac{1}{4}$ of four quarters of normal time; the distance between 30 and 36 to $\frac{1}{16}$ th $\frac{1}{4}$ of four quarters of normal time; that between 30 and 37 to $\frac{1}{8}$ th $\frac{1}{4}$ of four quarters of normal time, that between 30 and 38 to $\frac{1}{4}$ th $\frac{1}{4}$ of normal time, that between 30 and 39 to two quarters $\frac{1}{2}$ of normal time and finally that between 30 and 40 to four quarters $\frac{1}{4}$ of a 10 normal time. In the case considered, the device 31—32 will sign the conventional linear mark corresponding to the duration of the note played, while the printing elements 40' . . . 36', are located in correspondence to the points 40, 39, 38, 15 37 and 36, and each of which is provided at its end with a printing type 40'' . . . 36''. Each of the printing elements is supported by an individual support 41, (it being also possible to provide a support common to several devices, as indicated for 36, 37), and is urged by a spring 42 in the direction of the arrow 43, i. e. in such a manner as to withdraw the printing ends 40'' . . . 36'' from the paper sheet 6.

20 A rod 44, arranged parallel to the portion of paper included between the points 35 and 40, is held by rollers 45 and 46; the roller 45 receives a motion of rotation in the direction of the arrow 47 that may be either continuous and uniform or periodical and that will preferably be regulable; said motion is such that a lug 48, carried by said rod 44, moves in the direction of the arrow 29 with a linear speed equal to that with which the paper strip 6 moves in the same direction. In other words, the lug 48 moves in synchronism with the paper, i. e. it faces as long as the note lasts, always the same point of paper moving in the direction 29, and therefore after $\frac{1}{16}$ th of four quarters of normal time, it faces the element 36', after $\frac{1}{8}$ th of four quarters of normal time it faces the element 37', and so on until after four quarters of normal time it faces the element 40'.

25 In order that the motion in the direction of the arrow 29 for the element 44, may start simultaneously with the working of the writing point 32, there is provided a solenoid 49, which is operated by the current operating the solenoid 31, and the core 50 of which carries a wheel 51 30 that, due to the operation of the solenoid, is urged in the direction of the arrow 52 toward the wheel 45, thus reacting against the spring 61.

35 The working of the device is the following. Whenever one of the keys 1 is pushed down- 55

wardly, the contact device 70 is closed, the electro-magnet 31 is excited and the core 32 moves to the right so as to bring its point against the ribbon 33 thus tracing on the sheet 6, a line 5 that will be more or less long, the length of such line depending on the period of time for which the key 1 is pushed downwards.

Opposite the elements 36', 37' . . . 40', there 10 are provided solenoids 56' . . . 60' the respective cores of which 56 . . . 60, normally pushed in the direction of the arrow 43 by the springs 61, will all be simultaneously pushed in the direction of the arrow 62 at both the beginning and the 15 end of a note; in fact the part A of the contact device 70 descending with the key 1, will first bear against the movable contact element B normally resting on the contact element C whereto is connected the circuit of the solenoids 36', 37' . . . 60', and will cause the closure of the 20 circuit itself. Continuing its motion, the part A will rock the element B from engagement with the element C thus interrupting the said circuit, and it will bear against the contact element D of the contact device 70 and will close the circuit 25 relating to the solenoids 31 and 49.

At the moment when the note is terminated, the part A of the contact device 70, following the motion of the key 1, will disengage the element D and interrupt the circuit relating to 30 the solenoids 31 and 39, the spring B will come again to bear against the element C thus closing for a moment the circuit between C and A and causing the action of the solenoids 56' . . . 60'; the one of such solenoids disposed opposite the 35 lug 48, transmitting a push to the respective printing key type.

The operation

Whenever the key 1 is pushed downwards, the 40 part A of the contact device 70, through the movable contact element B normally bearing against the element C, closes for a very short while the circuit of the solenoids 56' . . . 60', the action of which, however, does not cause the operation of 45 the printing elements 36' . . . 40', due to the fact that the thickness of the element 44 is less than the sum of the distance between them and of the range of movement of the cores 56 . . . 60; subsequently, under the action of the part A the element B is disengaged from the element C thus 50 interrupting the related circuit, said part A then coming to bear against the contact element D closing the circuit of the solenoids 31 and 49. In consequence of this, the element 31, with the 55 interposition of a printing ribbon or the like, comes in contact with the paper strip 6 whereupon it impresses a linear mark the length of which will be proportional to the duration of the note, while the solenoid 49, by means of the wheel 60 51, presses the rod 44 against the small roller 45 revolving with uniform and preferably adjustable speed, the roller 45 thereby moving the rod 44 and the lug 48 upwards in the direction of the motion of the paper strip and maintaining the lug 48 opposite that point of paper where the element 31 has commenced to impress the linear sign. At the end of the note, when the key 1 is released by the hand, the part A closes for an instant the circuit of the solenoids 56' . . . 60' while 65 opening that of the solenoids 31 and 49; thus the lug 48, which stands opposite one of the elements 36' . . . 40', is caused to push said element in the direction of the arrow 62 against the sheet of paper, so that the printing part of such element, (in co-operation with a printing ribbon or the

like) will leave a mark on the paper sheet in correspondence to the point where the core (32) started to draw the line. This is possible as the element 44 is still held for a short while between the two rollers 51 and 45, in the same manner as 5 between two knife pins; in this way, however, the element 44 performs a slight oscillation compressing the small spring 12 through the thrust wheel 13. A fork element 74, fixed at 75 to a stationary part of the machine, forms a stop for 10 a spring 76 which at the bottom bears against an abutment 77 of the rod 44, and which, as soon as the rod 44 is released, pushes the latter downwards in opposite direction to the arrow 29; said rod 44 is also provided with another collar 78 15 which, in co-operation with the fork 74, serves to limit its downward movement so as to restore the lug 48 to its initial position before the core 32. 20 79 denotes a suitable support, (consisting, for instance, of hardened rubber), adapted to offer 25 support to the paper during the writing operation; 80 is a longitudinal strip disposed transversely of the paper strip; which is illuminated from the bottom by the lamp 81 and which provides at 82 a means of reading the printed matter, the strip 80 being of transparent material, such as, for instance, of polished glass; 83 denotes another transverse scale of reading which is equal and in position correspondent in the direction of its length to the aforesaid scale 82, 30 and which is adapted to receive, through the button 84, the fixed support 85 and the threaded rod 86, displacements in the direction of the arrows 87 so as to reduce or increase the distance between the two scales 82 and 83 and facilitate the measuring of the lengths of the printed notes. 35

With reference to the embodiment illustrated in Fig. 2, 1 is the keyboard of the musical instrument used, 101 the contact device of one of the keys, which is open when the key is in normal 40 position and which, when the key itself descends, pulls the contact element 102 across the contact element 103 and against the contact element 70a. An axle 145 rotates in the manner indicated by the arrow 47a and 48a is a hub fitted with a rocker 45 104 pivotally mounted at 104' and bearing at one end on the head of the bar 105 slidably mounted within the pipe 106 and supported by means of the pin 105', passing through the slot 105'', and engaging a spring 106' resting on the collar 106'', 50 somewhat distant from the types 36' . . . 113' . . . 40'. At the other end said rocker 104 rests on a terminal of the lever 114 that is under the action of the spring 115;—said lever 114 acts as a lock for the lever 116 provided with a key or shoe 116' 55 which can bear against the axle 45 through an opening 117 provided in flange 118 of the hub 48a;—119 is a spring tending to hold the lever 116 raised;—120 is a contact on the top of the lever 116 which in normal position rests on the contact 60 129 and closes the circuit of the solenoid 49; when said solenoid 49, by displacing the lever 114, enables the lever 116 to descend, the latter closing the circuit of the solenoid 121 which, being excited, acts on the rocker 104 causing it to rotate around 65 104', and therefore, by means of the bar 105, on one of the types 36' . . . 113' . . . 40' located on the sector 122;—123' are the types of the bemols and diesis, operated by the solenoids 124 the circuit of which reaches a black key 125 provided 70 with contacts which are equal in shape to those of a white key and which are connected directly to the contacts of the adjacent white keys;—3a is a roller for the paper strip 6 which, unrolling from the guide rollers 10a, 11a and 12a fixed on the 75

support 126, and passing beneath a printing ribbon or the like 33^a winds around the roller 7^a set in motion, in the direction of the arrow 28^a, by the roller 25^a; the latter roller being operated by a suitable motor, has a controllable speed by means of a known device, not shown, and is held in continuous contact herewith by means of a spring 128 working in a guide 127 and pushing the roller 7^a in the direction of the arrow 128', insures the paper 6 maintaining a uniform speed independently of the variation of the diameter of the rollers 3^a and 7^a themselves. 36" . . . to 40" and 107" to 113" are the heads of the printing types, provided with the marks suitable for the respective values; 123" are the heads of the printing types bearing the marks of the diesis and of the bemols that may traverse passages arranged in the type 36"; the breadth of the type 36' as well as its position in the total scale of the values considered, (the angle embraced by the sector 122, the extension of which corresponds to a semibreve $\text{---} = 4/4$), correspond to that of $\frac{1}{8}$ th (J). The whole of the types reproduces the usual musical divisions, while the values of the ternary tempos, as well as the minimum values of the binary tempos, are omitted. Thus the distance between a point 136 (which, at the beginning of a note that will last, for instance, $\frac{1}{8}$ th (J) is at the same distance as that existing between 36" and 37", and which, at the expiration of this fraction of time will be—in consequence of the displacement of the paper strip 6—in correspondence to the printing type 36") and the point where the type 36' prints, is equal to the time value of $\frac{1}{8}$ th (J);—that between said point 136 and the type 37" is equal to $\frac{1}{8}$ th (J); that between 136 and 107" is equal to $\frac{1}{8}$ th (J); that between 136 and 38" is equal to $\frac{1}{4}$ th (J); that between 136 and 108" is equal to $\frac{1}{8}$ th (J); that between 136 and 109" is equal to $\frac{3}{8}$ th (J); that between 136 and 39" is equal to $\frac{2}{4}$ th (J); that between 136 and 110" is equal to $\frac{5}{8}$ th (J); that between 136 and 111" is equal to $\frac{3}{4}$ th (J); that between 136 and 112" is equal to $\frac{7}{8}$ th (J); that between 136 and 113" is equal to $\frac{1}{4}$ th (J); finally, the distance between the point 136 and the type 40" is of $4/4$ th (A).

It follows that the point 136 which, during a fraction of time equal to $\frac{1}{8}$ th has come opposite the type 36", continuing its motion of translation in the same direction will successively come opposite all of the types composing the whole scale of values considered, and after $4/4$ th (A) will face the type 40"; considering that the bar 105 has simultaneously covered the corresponding angular distance, that is, that embraced between the heads 36" . . . 40", it appears that also said bar will face the respective side of the same type and that it, when the electro-magnet 121 is energized, will print the corresponding mark on the paper strip 6, and more exactly on the point 136.

Due to the fact that there is not, in the music, a sign suitable for the value of the types 108" and 110", also for the automatic transcription, it is necessary to resort to the expedient generally employed; the corresponding graphic will be printed with the sign of the preceding type (38" and 39") followed by a small line adapted to replace the sign (—) used in these cases to increase the value of a note of the fourth part of the value itself, this system being above all practical since that in general the increase of the value of a note in this degree is consequence of a "legato di valore" with the first note of the immediately following group.

The working of the device schematically illustrated in Fig. 2, is as follows: Assuming the parts 45^a and 25^a to be set in motion, with a minimum speed and by means of a motor, not shown, the axle 45 will thus revolve in the direction of the arrow 47^a with a predetermined speed, so that the small bar 105 of the hub 48^a will travel through the underlying sector 122 in a time equal to the duration of four quarters of slow rhythm; the roller 25^a revolves simultaneously with the consequent passage of the paper from the roller 3^a on the guide pulleys 10^a, 11^a, 12^a and on the roller 7^a so that a point of the paper remains always opposite the printing type that, at its other end, faces the point of the element or bar (105). 15

By depressing a key 1 (white key) of the instrument used, the descent of the blade 102 will close for a very short period of time, the circuit of the solenoid 49^a, after which such blade will bear against the contact 70^a until the key is released by the hand for returning to its normal position.

The solenoid 49^a that is excited, will give the rocker 104 a thrust in the direction of the arrow 52^a and therefore also the lever 114, which lever, revolving around 114', will release the lever 116 25 that, under the action of the spring 119, rotates around 116", opens the contact 120—129 and closes the contact 120—130 and couples by means of the shoe 116', the hub 48^a on the axle 45^a thus compelling such hub to follow the motion of rotation of the axle 45^a and displacing therefore the lower point of the small bar 105 along the sector 122. If the key 1 is lifted, the small blade 102 will close again the relative circuit with 103—120; this time, however, due to the commutation between the contacts 129 and 130 caused by the displacement of the lever 116, the solenoid 121 will be excited; this will transmit a thrust in the direction of the arrow 104" to the rocker 104 and therefore also to the small bar 105 and to the lever 116;—while the small bar 105 will push the head of the one of the types 36" . . . to 40", 107" to 113" in front of which it will be at the moment of the thrust, causing it to print on the paper strip 6, the lever 116 will be restored to the initial position, and therefore the hub 48^a that has been uncoupled from the axle 45, will be restored to the initial position by the spring 131 and will be ready to re-start the operation.

As it is possible that a note may have a duration greater than that expressed by the type 40" and as it is not convenient to prolong the sector 122 for such an exceptional case, a special circuit has been provided;—the small pipe 106, when in rest position, bears against an abutment 132 forming part of a normally open spring contact device 133; said device being in a circuit which, on one side is connected with contact 70^a whereupon the contact element 102 rests throughout the duration of the note, and on the other side with the circuit 132"—120.

When the small bar 105 has been set in motion and has reached the end of its movement opposite the key head 40' it finds the fixed contact 134 which, through the closed contact 120—130, 65 causes the energization of the solenoid 121, the printing of the type 40" representing the maximum value (4/4-one $\frac{1}{8}$ semibreve) and the consequent very rapid return of the hub 48^a to its normal position by means of the spring 131. The contact 102 being still engaged with the contact 70^a, the contact 133—132—132', which is momentarily closed by the small pipe 106 causes the excitation of the solenoid 49^a, the further motion of the hub 48^a and therefore of the small bar 75

105 along the sector 122, motion that can be repeated over for the entire duration of the sound and the consequent contact between the contact elements 102 and 70^a.

5 Having now particularly described and ascertained the nature of the present invention and in what manner the same is to be performed, the claims are:

1. In a device for automatically printing music, 10 a keyboard including keys, a music strip, means for moving said strip at a uniform speed, a plurality of groups of note printing type members, each group of type members corresponding to one of said keys and all of the keys of said group 15 being arranged to print the representation of the corresponding note on said strip, the several type members of each group being relatively displaced in the direction of movement of said strip and adapted to print notes of different time 20 values, and means actuated at the return of the key following a depression thereof to operate the related type member having a time value corresponding with the period of depression of said key.
- 25 2. A printing device as claimed in claim 1 characterized in that the last mentioned means includes a member set in motion upon the depression of any one of said keys and moving in synchronism with said strip.
- 30 3. A printing device as claimed in claim 1 characterized in that the last mentioned means includes a member set in motion upon the depression of any one of said keys and moving in syn-

chronism with said strip, and means coating with the last mentioned member to engage and operate the printing member having a time value corresponding with the duration of movement of said member.

5 4. A printing device as claimed in claim 1 characterized in that the last mentioned means includes electromagnetic actuating means for the type members normally disposed out of range of coaction with said type members, and means actuated to an extent dependent upon the duration of the depression of the related key to form a coupling between the electromagnetic means and one of said type members.

15 5. A printing device as claimed in claim 1 characterized in that the last mentioned means includes electromagnetic actuating means for the type members normally disposed out of range of coaction with said type members, means actuated to an extent dependent upon the duration of the 20 depression of the related key to form a coupling between the electromagnetic means and one of said type members, and means acting on the release of a key to restore the last mentioned 25 means to initial position.

6. A printing device as claimed in claim 1 characterized in that the last mentioned means includes a rotatable member associated with each group of type members, and means operated on 30 depression of a key to initiate rotation of said rotatable member.

JURIY BARSUK.
